UNITED STATES PATENT OFFICE.

GEORGE HENRY WHEARY, OF RACINE, WISCONSIN

TRUNK-LOCKING MEANS.

1,158,412.

Specification of Letters Patent.

Patented Oct. 26, 1915.

Application filed June 29, 1914. Serial No. 847,808.

To all whom it may concern:

Be it known that I, GEORGE H. WHEARY, a citizen of the United States, and resident of Racine, in the county of Racine and State of Wisconsin, have invented new and useful Improvements in Trunk-Locking Means, of which the following is a description, reference being had to the accompanying drawings, which are a part of this specification.

This invention relates to improvements in trunk locking means more particularly adapted for use with trunks having a plurality of locking bolts.

In trunks of the better class a plurality of keyed locking devices is usually provided for locking the trunk cover to the body portion. The independent operation of these locking devices is not convenient and requires considerable time and is otherwise objectionable.

It is one of the objects of the present invention to overcome the before mentioned objectionable features and provide a trunk locking means which may be controlled by a keyed engagement with one of the locks.

A further object of the invention is to provide a trunk locking means in which the unlocking and outward movement of the hasp member of one of the locks will automatically unlock the hasp member of another lock.

A further object of the invention is to provide a trunk locking means which is of simple construction, is strong and durable and which is well adapted for the purpose described.

With the above and other objects in view, the invention consists of the improved trunk locking means and its parts and combinations as set forth in the claims and all equivalents thereof.

In the accompanying drawing in which the same reference characters indicate the same parts in all of the views, Figure 1 is a front view of a trunk provided with the improved locking means; Fig. 2 is a vertical sectional view of the trunk and an inner view of the locking means thereof; Fig. 3 is a sectional detail view on a larger scale taken on line 3-3 of Fig. 2; Fig. 4 is a sectional detail view of one of the locking members shown in locked position; Fig. 5

is a similar view with the parts shown in open position; and Fig. 6 is a sectional detail view of one of the locking members.

Referring to the drawing the numeral 8 indicates the trunk body and 9 the hinged cover thereof. The cover is locked in closed position by two hasp locks 10 and 11, of which the lock 10 is the keyed lock and the lock 11 is automatically controlled by the keyed lock. The lock 10 comprises the spring hasp member 12 hinged to the cover and the escutcheon member 13 secured to the body portion of the trunk. The hasp member is provided with the usual locking barrel 14 which enters the trunk through the barrel opening 15 of the escutcheon member 13 and the bolts 16 of said barrel 16 member lock the two parts together in the ordinary manner. The hasp member 12 is also provided with an inwardly projecting finger 17 having an inclined end portion 17' the purpose of which will later be described. This finger extends through an opening 18 in the escutcheon member when the parts are in closed position.

The hasp member is provided with a spring 19 for yieldingly holding the said member in its outer open position. The automatically operated lock 11 is of the keyless form and comprises the spring hasp member 20 which is hinged to the cover and is adapted to swing into engagement with the escutcheon member 21 mounted on the body portion of the trunk. The escutcheon member is provided with an eyed projection 22 which extends into the trunk through an opening 23 formed in the escutcheon member 21 and which is entered by a bolt 24 slidably mounted within a tubular portion 25 of the said escutcheon member. The bolt 24 is provided with a guide stem 26 which passes through a medially positioned guide partition 27 of the tubular portion 25 and is limitedly, slidably connected to an actuating rod 28 slidably mounted on the inner side of one of the walls of the trunk. The outer end of the bolt stem extends slidably through a yoked end 29 of the actuating rod and is held in engagement with said rod yoke by a transverse pin 30. The yoke portion 29 is of a length to permit the bolt stem to reciprocate therein a sufficient distance so that the bolt may be pushed into unlock-

ing position by the eyed projection 22 of the hasp member when the hasp member is pressed into locking engagement with the bolt.

5 A heavy unlocking coiled spring 31 surrounding the bolt stem 26 and interposed between the yoked end 29 and the medial partition 27 serves to normally hold the bolt in unlocked position. A locking coiled 10 spring 32 also surrounding the bolt stem and interposed between the medial partition and the rectangular head 24' of the bolt is of less strength than the first mentioned bolt spring and is adapted to yieldingly 15 hold the bolt in hasp engaging position when the unlocking spring is compressed by the actuating rod 28. The locking end of the bolt is beveled as indicated by the numeral 33 and the inner end 34 of the eyed 20 projection 22 is likewise beveled to provide for the automatic engagement of the two parts when the hasp member is pushed into locked position.

The actuating rod 28 extends through 25 guide brackets 35 to a position so that its angular end portion 36 will be engaged by the angular face of the projection 17 and the rod will be moved endwise in a direction toward the spring actuated bolt and will 30 compress the heavy spring and permit the light spring to yieldingly move the bolt to locking position. The keyless clasp member is also provided with a spring 37 to swing the said member to open position.

35 In use the trunk cover is closed and the key lock hasp member is first swung to locked position and when locked the other hasp member may then be pushed inwardly to locked position. In unlocking the trunk 40 it is only necessary to unlock the keyed hasp member and the other hasp member will be automatically unlocked and will spring to open position.

While the trunk is shown as having but 45 two locks it is to be understood that any number of locks may be used and controlled from one keyed lock.

From the foregoing description it will be seen that the trunk locking means for 50 trunks having a plurality of locks is of simple construction and is well adapted for the purpose described.

What I claim as my invention is:

1. The combination of a trunk, of an automatic locking means therefor, consisting of a plurality of locking members for locking the cover to the body portion, one of said locking members being controlled by a key and the remaining member being yieldingly 55 controlled by a movement of the keyed lock toward open position, said remaining locking member adapted to be lockingly engaged while held in locked position by the keyed locking member.

2. The combination of a trunk, of an automatic locking means therefor, comprising a plurality of locking members for locking the cover to the body portion, one of said locking members being controlled by a key and the remaining member being yieldingly 70 controlled by a slideable rod which holds the remaining locking member yieldingly in locking position until the rod is disengaged by the keyed lock.

3. An automatic locking means, comprising 75 a keyless hasp member, a bolt member positioned to engage the hasp member, means for yieldingly holding the bolt member in unlocked position, means for yieldingly holding the bolt member in locked position, 80 a keyed hasp member spaced from the keyless hasp member, an escutcheon plate engaged by the keyed hasp member, and a member engaged by the keyed hasp member when in locked position for yieldingly 85 holding the bolt in locking position.

4. An automatic locking means, comprising 90 a keyed hasp member, a bolt member positioned to engage the hasp member, an actuating member having a slideable connection with the bolt, a coiled spring engaging the bolt and the actuating member and exerting a tendency to move the bolt to unlocking position, means of less tendency 95 for moving the bolt to locking position, and a keyed hasp member having means for moving the actuating member to compress the coiled spring.

5. An automatic locking means comprising 100 a hasp member, a bolt member positioned to engage the hasp member, an actuating member having a slideable connection with the bolt and an angled end portion, a coiled spring engaging the actuating member and the bolt and exerting a tendency 105 to move the bolt to unlocking position, means of less tendency for moving the bolt to locking position, and a keyed hasp member having a projection with an angled portion which engages the angled end of the 110 actuating rod and moves said rod to compress the coiled spring.

6. An automatic locking means, comprising 115 a keyless hasp member, a lock casing, a bolt slidably mounted within said casing and provided with a stem, and positioned to engage the hasp member, the casing being provided with a medial guide partition through which the stem projects, an actuating rod slidably engaging the bolt stem, 120 a coiled spring surrounding the bolt stem and interposed between the medial partition and the actuating rod, another coiled spring surrounding the bolt stem and interposed between the medial portion and the 125 bolt, said last mentioned spring being of less strength than the first mentioned spring, and a keyed hasp member having a pro-

jection with an angled portion which engages the angled end of the actuating rod and moves said rod to compress the first mentioned coiled spring and permit the 5 spring of less strength to move the bolt to locking position.

In testimony whereof, I amx my signature, in presence of two witnesses.

GEORGE HENRY WHEARY.
